UNITED STATES PATENT OFFICE.

EMIL TYDEN, OF EVANSTON, ILLINOIS.

SEAL.

Application filed May 2, 1923. Serial No. 636,075.

To all whom it may concern:

Be it known that I, EMIL TYDEN, a citizen of the United States, and resident of Evanston, in the county of Cook and State of Illinois, have invented certain new and useful Improvements in Seals, of which the following is a specification, reference being had to the accompanying drawings, forming a part thereof.

10 The purpose of this invention is to provide an improved and very simple form of seal adapted for sealing cars, doors and the like, by a looped member engaged with staples or the like. It consists in the elements 15 and features of construction shown and described as indicated in the claims.

In the drawings:—

Figure 1 is a plan view of a seal embodying this invention in the form in which it is 20 furnished for use and before it has been used.

Figure 2 shows the seal in closed and sealing position,—that is, with its previously free end engaged with the body, completing 25 and closing the sealing loop.

Figure 3 is an enlarged plan view of the body and loop ends engaged therewith at sealed position.

Figure 4 is a section at the line, 4—4, on 30 Figure 3.

Figure 5 is a section at the line, 5—5, on Figure 3.

Figure 6 is a plan view of a sheet metal blank upon which the body of the seal is 35 formed by stamping.

Figure 7 is a detail side elevation of a portion of the loop member or rod of which it is formed, having certain V-shaped notches for determining the folding of the said rod 40 to form a hook in its sealed position and insuring its breaking upon the straightening of the hook.

The construction shown in the drawings 45 comprises a body member, A, and a loop member, B. The body member, A, is desirably and as shown, formed of a sheet metal blank shown in Figure 6 which is cut from the sheet metal with four wings projecting from four sides of its central portion 50 and adapted to be folded up at the four sides to enclose an open space, and constitute an open-topped box or cup with a web bottom. Two of the opposite sides, A¹, A¹, have each an aperture, a¹, said apertures being, when 55 the sides are folded up, aligned with each other in one direction transverse to the body

member. The other two sides, A², A², have apertures a², a², which when the sides, A², A², are folded up are similarly aligned with each other in a direction transverse to the 60 direction of alignment of the apertures, a¹, a¹. The apertures, a¹, a¹, are round to admit loosely and approximately to fit the rod of which the loop member, B, is formed. The apertures, a², are elongated parallel to the 65

alignment of the apertures, a¹, a¹, for admitting through them certain flattened and widened portions of the rod forming the loop, B, said flattened portions having no specific function with respect to the sealing, 70 but being designed to receive identifying markings. The flattened portion, b^x, at the end being desirably marked to identify the ownership of the car or other receptacle which is sealed, and the flattened portion, b^y, 75 being formed at a portion of the loop rod which will not be detached in breaking the seal and designed for receiving a serial number by which the seal may be identified.

The loop member, B, desirably being a rod 80 or wire, has one end portion permanently secured to the body member, A, said securement being effected by inserting said end portion through the aligned apertures, a¹, a¹,—which apertures are desirably, as shown, 85 at a distance above the bottom web of the body member substantially equal to the diameter or thickness of the loop rod, B,—and sinking the portion, B¹⁰, of the rod between the two side walls, A¹, A¹, of the body 90 member onto the bottom web of the body member, forming small shoulders, b¹⁰, b¹⁰, tightly jammed between the two walls, A¹, A¹, and simultaneously by the same stamping operation which is performed with suitable dies, flattening and expanding laterally the rod just outside of each of said walls, A¹, A¹, as seen at b¹, b¹. The side walls, 95 A², A², are folded up of greater width than the other side walls, A¹, A¹, the excess width 100 being folded outward, forming flanges, A³, A³, as seen most clearly in Figure 4. The purpose of these flanges will hereinafter appear.

The free end portion B³⁰ of the loop rod 105 beyond the loop, B, and beyond the number-bearing flattened areas, B^y, is desirably bent or folded at b⁴, to extend nearly at right angles to the immediately preceding portion, and thereby nearly at right angles to the initial portion, B¹, and so as to point toward the elongated apertures, a², a², through 110

which said end is to be inserted, the curve of the loop, B, being such that upon applying pressure to close the two sides of the loop together, the flattened end, b^1 , will normally be thrust directly through the two apertures, a^2 , a^2 , and the portion of the loop rod adjacent to the bend, b^4 , extends across above the portion, B^{10} , of the initial or secured end of the rod, as seen in Figure 5. 10 At a point on the rod which will be outside the body member when the rod has been thrust through the apertures, a^2 , a^2 , to bring the bend, b^4 , up against the edge of the flange, A^3 , of the side wall first entered by the flattened end of the rod, the rod is by construction provided with two V-shaped notches, b^3 , b^3 , on the upper or outer side. The purpose of these notches is, first to facilitate the folding of the portion of the 20 rod which projects beyond the body back over the adjacent side wall, A^2 , and its flange, A^3 , to form a hook B^{21} , projecting back across the open side of the box constituting the body member, as seen in Figures 2, 3 and 4; and secondly to insure a 25 certain limit of width of the hook,—that is, to insure that the fold B^{22} , to form the hook shall be at a predetermined point or place; because the wire will certainly fold at the 30 points where it is weakened by these V-shaped notches. A third purpose, and the chief purpose, of the V-shaped notches is to insure the breaking of the rod at the bend of the hook if and whenever it is straightened, as it must be in order to open the seal 35 for detaching it from the sealed receptacle. Upon consideration of the structure shown, it will be understood that when the detachment of the seal from the sealed object is authorized, such detachment will be 40 effected by straightening the hook, resulting in breaking off the end at the notches, b^3 , b^3 , and withdrawing the end thus mutilated from the body member, and thereby opening the loop so that it can be disengaged 45 from staples or whatever it may be engaged with in sealing. It will also be understood that it is designed that any unauthorized attempt to tamper with the seal will be disclosed by the fact that such tampering will 50 break the hook at the notches, b^3 . It will be recognized also that the opening of the loop for detaching the seal can be effected without breaking the hook, only if some other 55 means of disengaging one end or the other of the loop rod from the body member can be found; and it will be understood that the purpose of sinking the secured end of the 60 loop rod between the sides, A^2 , A^2 , of a body member and the purpose of flattening and broadening the rod at b^1 , b^1 , outside of said sides, is to make it impossible to detach the secured end of the rod from the body member without breaking the rod,—as may 65 easily be done at the flattened portion, b^1 , on

the side of the body toward the loop,—or by severing the walls of the body member at the apertures through which the loop rod extends, so as to disengage the loop rod laterally. It will be understood that mere severance of the walls, A^1 , A^1 , from the apertures, a^1 , to the edges of the walls, will not make it possible to detach or withdraw the secured end because that end is crossed by the other end portion of the rod, as seen in Figure 5; and even the opening of adequate gaps from the aperture, a^1 , to the upper edges of the walls, A^1 , A^1 , would not permit the lifting out of the attached end of the rod. It will be understood, upon consideration further, that by reason of the flanges, A^3 , A^3 , on the side walls, A^2 , A^2 , it will be impossible to make openings in these side walls for lifting out the rod which is inserted through these walls, because for such openings it will be necessary, first, to cut through the side walls above the apertures, a^2 , including the flange, and it will then be necessary to fold the severed edges laterally to create a gap as wide as the diameter of the rod; but it would be impossible thus to fold laterally the angular lip which would be produced by the slit or cut; and it would be first necessary to straighten up the flange before making the cut or attempting the lateral folding to open the gap for removal of the rod; and by reason of the predetermined of the width of the hook which is effected by the spacing of the V-shaped notches, b^3 , b^3 , so that that width is less than the width of the flange, A^3 , it will be impossible to straighten up the flange, A^3 , before opening the hook, and impossible to open the hook without breaking.

By the various expedients and features of construction above described, the possibility of tampering with the seal so as to open it without such mutilation of one or the other of its members as to make obvious at a glance that it has been tampered with, is effectually prevented.

I claim:—

1. A seal comprising a body member having walls encompassing an open space, said walls having two pairs of opposed apertures in two planes transverse to each other and to the plane in which said walls encompass the open space; in combination with a flexible rod, one end of which is inserted through one pair of said apertures across said open space and locked in said apertures by distortion of the rod at opposite sides of the two walls respectively, the other end of the rod being adapted for insertion through the other pair of apertures, and at a point far enough back from the end to form a hook, being weakened so as to insure breaking by being folded into hook form and subsequently straightened.

2. In the construction defined in claim 1,

foregoing, the body member being a sheet metal stamping in cup form, the apertures in the walls through which the secured end is inserted being at a distance above the bottom substantially as great as the thickness of the rod, the distortion of the rod for locking it in the first mentioned pair of apertures consisting in sinking it to the bottom between the walls through which it extends.

3. In the construction defined in claim 1, foregoing, the rod being by construction bent in an open loop between its ends, the unattached end portion being further bent crosswise of the loop to point the end nearly at right angles to the secured end portion and in a position for entering the second pair of apertures by flexing the loop to reduce its spread.

4. In the construction defined in claim 1, foregoing, the distortion of the rod for locking it in the first mentioned pair of apertures comprising flattening and laterally expanding the rod at the outer sides of the two outer walls through which it extends.

5. In the construction defined in claim 1, foregoing, the wall through which the final end of the rod is inserted and over which it is flexed in hook form being flanged, rendering it at the location of the aperture, angular in cross section in a plane transverse to the secured end portion of the rod; whereby severance and opening of the wall for release of the hooked end of the rod without obvious mutilation of the body member is prevented.

6. In the construction defined in claim 1, foregoing, the body being in cup form comprising a bottom web, the initially secured end portion of the rod being sunken toward the bottom web between the walls through which it extends, forming stop shoulders at the inner sides of said walls preventing longitudinal withdrawal, and the other pair

of apertures being positioned for locating 45 the finally inserted end above the initially secured end portion; whereby the finally engaged hook end portion prevents lateral removal of the initially secured end portion.

7. In the construction defined in claim 1, 50 foregoing, the weakening of the rod at the point for bending it to hook over the other body being by V-shaped notches on the side of the rod toward which the end is to be folded to form a hook.

8. In the construction defined in claim 1, foregoing, one of the walls through which the final end of the rod is inserted and over which it is flexed in hook form being flanged, rendering it at the location of the 60 apertures angular in cross-section in a plane transverse to the first secured end portion of the rod, the weakening of the rod at the point for bending the hook over said wall being by means of two V-shaped notches on 65 the side toward which the end is to be folded to form the hook, said notches being spaced apart a distance enough less than the width of the flange which renders the wall angular in cross-section, to insure thereby 70 the width of the hook gap being less than the width of the flange, for defeating the unfolding of the flange into the hook.

9. In the construction defined in claim 1, foregoing, the wall through which the final 75 end of the rod is inserted and over which it is flexed in hook form being formed to extend from the aperture to the free edge in more than one plane transverse to the inserted rod, whereby folding of the apertured 80 wall after slitting it from the aperture to the edge to open a path for lateral removal of the rod is prevented.

In testimony whereof, I have hereunto set my hand at Chicago, Illinois, this 30th 85 day of April, 1923.

EMIL TYDEN.
